Patented Dec. 12, 1967

209,527

MUSICAL CAROUSEL TOY

Robert I. Genin, Scarsdale, N.Y., assignor to Child Guidance Toys Inc., Bronx, N.Y., a corporation of New York

Filed Dec. 30, 1966, Ser. No. 5,244

Term of patent 14 years

(Cl. D34—15)

Fig. 1.

Fig. 2.

FIG. 1 is a perspective view of my design for a musical carousel toy;

FIG. 2 is a side elevational view of the toy;

FIG. 3 is a plan view of the toy;

FIG. 4 is a rear elevational view of the toy; and

FIG. 5 is a front elevational view of the toy.

I claim:

The ornamental design for a musical carousel toy, substantially as shown.
